BRAKE BEAM

Robert B. Cottrell, Chicago, Ill., assignor to American Steel Foundries, Chicago, Ill., a corporation of New Jersey

Application October 24, 1947, Serial No. 781,900

6 Claims. (Cl. 188—226.1)

1

This invention relates to brake beams and has particular reference to a truss type beam of novel construction.

A general object of the invention is to design a brake beam wherein the truss structure and brake heads are integrally formed as a single casting.

Another object of the invention is to design a novel brake beam such as above described wherein in each end of the beam is formed with a guide lug adapted for reception within an associated support structure, such as a bracket, on the side frame of a railway car truck.

A further object of the invention is to design a truss type brake beam of simple economical construction and light weight and which shall have extreme stiffness and absence of deflection at the rated load of such beams.

A still further object of the invention is to design a beam of the character under consideration possessing a maximum amount of strength with a minimum amount of material by constructing the tension and compression members of special form in cross section, and by so distributing the material as to produce the necessary strength at the particular points in the beams which experience has proved are most apt to yield and break when subjected to the heavy loads and strains incident to their use.

The foregoing and other objects and advantages of the invention will become apparent from a consideration of the specification and the drawings, wherein:

Figure 1 is a fragmentary top plan view of one embodiment of the invention;

Figure 2 is a front view of the structure shown in Figure 1;

Figure 3 is an end view of the structure shown in Figure 1; and

Figures 4 to 7 are fragmentary sectional views taken respectively in the planes indicated by lines 4—4, 5—5, 6—6 and 7—7 of Figure 1.

Figure 8 is a fragmentary top plan view of a modification of the invention;

Figure 9 is a front view of the structure shown in Figure 8; and

Figure 10 is an end view of the structure shown in Figures 8 and 9.

Describing the invention in detail and referring first to the embodiment illustrated in Figures 1 to 7, inclusive, the novel brake beam comprises a cambered channel or U-section compression member 2, tapering in thickness from the transverse center line of the beam toward each extremity thereof as may readily be seen

2

in Figure 2. The compression member includes an arcuate rear web 8 and top and bottom flanges 4 and 6, as best seen in Figure 7. The web 8 may be cored away at spaced points on its neutral axis intermediate the midpoint and each end of the compression member to form oval-shaped openings 10, 10 elongated longitudinally of said compression member. These openings are designed not only to reduce the weight of the beam but also to accommodate bending and deflection of the compression member in the plane of the beam when loaded. A bead 12 may be formed around the marginal edges of each opening on the inner face of the web 8 to strengthen the construction.

At each end of the compression member (only one end of the beam being shown inasmuch as it is identical at its opposite ends) the top and bottom flanges 4 and 6 converge as at 14 and 16 (Figure 2) respectively, and with the rear web 8 merge into a flat web or gusset 18, said gusset being formed as a continuation of a longitudinal horizontal flange 20 of a T-section tension member, generally designated 22.

The tension member, in addition to the flange 20 which forms the leg of the T, comprises a longitudinal vertical wall or web 24 forming the head of the T.

The wall 24 of the tension member is continued along the forward edge of the gusset 18 and with the forward edge of the gusset merges into a front wall 26 of a conventional brake head, generally designated 28, the wall 24 merging into the inboard edge of said front wall 26 and the gusset merging into the rear surface of said front wall.

The brake head is formed with a conventional keyway 30 for reception of associated key means (not shown) for securing an associated brake shoe (not shown) to the front face of the brake head wall 26 in the conventional manner.

The rear surface of the front wall 26 of the brake head is formed with a vertical wall or rib 32 extending transversely of the beam and merging at its inboard side into the outboard edge of the gusset 18.

The gusset is connected at its rear edge to a flange 33 of a compression member wall 34 forming a T-section therewith, said wall 34 extending longitudinally of the beam and merging at one end into the inboard side of the transverse wall 32 of the brake head and said wall 34 merging at its other end with the top and bottom flanges 4 and 6 of the compression member at their converging portions 14 and 16 respectively.

The wall 34 serves as a stiffener for the gusset and provides a strong and light connection between the compression member and brake head and the gusset.

A vertical bead or wall 38 is formed on the inboard edge of the gusset, said bead terminating at one end at the juncture between the compression member and the gusset and merging into said top and bottom flanges 4 and 6 of said compression member, and at its other end the bead is continued for a short distance on the rear edge of the flange 28 of the tension member, and, as may be readily seen in Figure 1, the bead tapers off into said flange 28. It will be noted that the bead 38 adds to the rigidity of the gusset, affords a strong, light connection between the tension and compression members, and serves to distribute stresses more evenly over the entire area of the gusset.

The rear surface of the brake head wall 26 and the outboard surface of the wall 32 are integrally formed with a guide lug 48, preferably disposed in a diagonal plane and adapted for reception within an associated support bracket (not shown). The lug 48 is provided with substantially identical top and bottom recesses 42 adapted to lighten the beam and to form convenient receptacles for collecting foreign matter which may lodge in the associated guide bracket, thus reducing the tendency of such matter to deposit in the bracket forwardly of the lug 48, thereby restricting movement of the beam. The recesses preferably terminate inboardly of the outboard extremity of the lug 48 so that the latter bears at its outboard end against the associated support bracket along a continuous surface, thus preventing gouging of the bracket.

It may be noted that the lug 48 is provided on its top surface with a flange 44, merging into the outboard side of the brake head wall 32 at its rear extremity to afford a strong connection to the brake head. By means of this connection a relatively strong guide lug structure is provided, resulting in substantial economy in the manufacture of the beam.

The beam is provided at its transverse center line with a strut 46 connected between the compression and tension members 2 and 22, as best seen in Figure 1. The strut is, in general, a hollow cylindrical or tubular structure, flaring outwardly at its rear extremity and connected to the top and bottom flanges 4 and 6 of the compression member. The strut is provided with a brake lever slot 48 and a pin opening 50 traversing said slot and adapted for the reception of a pin (not shown) adapted to afford a fulcrum for a brake lever (not shown). The forward or front end of the tubular strut 46 emerges into the vertical wall 24 of the tension member and is connected at opposite sides thereof to the flange 28 of the tension member by horizontal webs 52, 52 (Figure 1). Thus it will be seen that I have devised a novel brake beam in which all the parts are integrally formed as a single casting to afford maximum strength with minimum weight.

Referring now to the modified embodiment of the invention illustrated in Figures 8 to 10, inclusive, it will be understood that the beam therein shown is substantially identical with that of Figures 1 to 7 except that the bead 38 at the inner edge of the gusset 18 is eliminated and the gusset is shortened. The parts of this beam corresponding to those of the beam shown in

Figures 1 to 7, inclusive, are identified by corresponding reference numerals.

It may be noted by reference to Figures 2 and 9, that the juncture of the compression member flanges 4 and 6, which converge as above described at 14 and 16, with the front flange 38 of the compression member wall 34, defines a wish-bone section in a vertical plane extending longitudinally of the compression member and intersecting said flanges. This construction has been found to afford unusually great strength and flexibility in railway service.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. A brake beam casting comprising a compression member having an end portion with a rear wall and a flange projecting forwardly therefrom, a tension member connected to said flange, a brake head connected to at least one of said members, said compression member having another portion of U-section including top and bottom flanges merging with said first-named flange to define a wishbone section inboardly of said head in a vertical plane extending longitudinally of the compression member and intersecting said flanges.

2. A brake beam casting comprising a compression member having a U-section portion with a rear web and top and bottom flanges, a tension member, a strut connecting the tension member to said portion, a brake head connected to said beam, said compression member having a T-section portion including a rear wall defining the head of the T and formed as a continuation of the first-mentioned rear wall, said last-mentioned portion comprising a front flange defining the leg of the T and connected to the tension member, said first-named flanges merging with said front flange to form a wishbone section inboardly of the brake head in a vertical plane extending longitudinally of said compression member and intersecting said flanges.

3. A brake beam casting, according to claim 2, wherein the rear wall of the U-section portion is provided with a plurality of openings spaced longitudinally thereof and adapted to impart flexibility to said portion.

4. A brake beam casting, according to claim 2, wherein a substantially vertical wall is connected to the front flange in the region of its merger with the first-named flanges and extending arcuately outboardly therefrom and then inboardly along the rear edge of the tension member, said vertical wall terminating intermediate the ends of the tension member.

5. A brake beam casting comprising a compression member having a U-section portion with a rear web and top and bottom flanges, a T-section tension member having a front wall forming the head of the T and a rear flange forming the leg of the T, a strut connecting the tension member to said portion, said compression member having a T-section end portion including a rear wall defining the head of its T and formed as a continuation of the web and including a front flange defining the leg of its T, said front and rear flanges being coplanar and merging at the end of the casting to define an end portion.

having an integral brake head member attached thereto, said top and bottom flanges merging with said front flange to define a wishbone section of the juncture between the U-section portion and the T-section portion of the compression member in a vertical plane extending longitudinally of said compression member and intersecting said flanges.

6. A brake beam comprising a truss including tension and compression members and brake heads at the ends thereof, said compression member having a central portion with top and bottom flanges and having a T-section portion at each end thereof including a rear wall having a front flange, said top and bottom flanges converging toward and merging with the front flange to define a wish-bone section in a plane approximately perpendicular to the plane of the truss

and extending longitudinally of the compression member and intersecting said flanges.
